UNITED STATES PATENT OFFICE.

WALTER E. SARGENT, OF MONTREAL, QUEBEC, CANADA.

DIE-SINKING MACHINE.

1,317,038.

Specification of Letters Patent. Patented Sept. 23, 1919.

Application filed July 24, 1917. Serial No. 182,450.

To all whom it may concern:

Be it known that I, WALTER E. SARGENT, a citizen of the United States, and resident of Montreal, in the county of Hochelaga, 5 Province of Quebec, Dominion of Canada, have invented a new and useful Improvement in Die-Sinking Machines, of which the following is a specification.

This invention relates to a machine for 10 sinking or engraving dies for the purpose of reproducing the same from a pattern or templet, either in cameo or intaglio, the said machine being automatic, accurate, and expeditious in operation.

15 One object is to provide a machine of this character in which the construction is such that the engraving tool may be caused to traverse a perpendicular surface and thereby enable the production of dies having vertical walls, as distinguished from walls at an angle of substantially ten degrees to the vertical which has been the closest approximation to vertical walls obtainable in prior machines.

20 Another object consists in providing a machine of this character which comprises means for cutting either right or left hand dies from a single given pattern, which dies may be the full size of the pattern.

25 A further object consists in providing a machine of this character in which the work holder is so mounted as to be adjustable in various directions for the purpose of facilitating angular cuts by the working tool.

30 A still further object consists in providing a machine of this character which effectively completes the die sinking operation so as to practically eliminate the necessity or desirability of hand work upon the dies 35 which have been cut thereby.

A still further object consists in providing certain improvements in the form, construction and arrangement of the several parts whereby the above named and other advantages may be effectively attained.

A practical embodiment of my invention is represented in the accompanying drawings in which,

40 Figure 1 represents a front elevation of the whole machine with the motor and belts for operating the tools removed.

45 Fig. 2 represents a side elevation of the same.

Fig. 3 represents a top plan view of the same.

55 Fig. 4 represents an enlarged detail side elevation of the base and adjacent parts.

Fig. 5 represents an enlarged detail front elevation of the structure shown in Fig. 4, parts being broken away to expose those 60 behind.

Fig. 6 represents a detail top plan view, partly in section, of the parts shown in Fig. 5.

65 Fig. 7 represents a detail vertical section on a still larger scale, taken in the plane of the line VII—VII of Fig. 6, looking in the direction of the arrows.

Fig. 8 represents a similar view taken in the plane of the line VIII—VIII of Fig. 6, 70 looking in the direction of the arrows.

Fig. 9 represents a detail section taken in the plane of the line IX—IX of Fig. 6, looking in the direction of the arrows.

75 Fig. 10 represents an enlarged detail section illustrating the means for connecting the work and pattern holders.

Fig. 11 represents an enlarged detail section showing the change speed mechanism which constitutes part of the drive of the 80 machine.

Fig. 12 represents an enlarged detail section showing the reversing mechanism which forms part of the drive of the machine.

85 Fig. 13 represents a detail end elevation of the parts shown in Fig. 12.

Fig. 14 represents an enlarged detail transverse section through the clutch and adjacent parts of the reversing mechanism 90 shown in Fig. 12.

Fig. 15 represents an enlarged detail longitudinal section through the said clutch mechanism.

95 Figs. 16, 17 and 18 represent detail side elevations of the said clutch mechanism in different positions.

Figs. 19, 20 and 21 represent enlarged detail elevations, partly in section, showing the clutch operating lever and associated mechanism in different positions.

100 Fig. 22 represents an enlarged detail longitudinal section showing the means for reciprocating the main bed and clutch for controlling the same.

105 Figs. 23 and 24 represent enlarged detail

side views, partly in section, showing the means for connecting and disconnecting the screw which drives the pattern support.

Fig. 25 represents an enlarged detail section through the means for driving the screws which actuate the work and pattern holders.

Fig. 26 represents an enlarged detail section through a friction clutch which forms part of the feeding mechanism of the machine.

Figs. 27, 28 and 29 represent enlarged detail elevations of a link connection which forms part of the feeding mechanism of the machine, the same being shown in different positions in the three views.

Figs. 30, 31 and 32 represent enlarged detail elevations, partly in section, of the segmental gear and pawl arrangement which imparts motion to the screws that actuate the work and pattern holders.

Fig. 33 represents a top plan view of the frame which carries the tracer and cutting tool.

Fig. 34 represents an enlarged detail side elevation, partly in section, of the tool carrying frame and associated parts.

Fig. 35 represents a view similar to Fig. 34, parts being broken away to disclose those behind.

Fig. 36 represents an enlarged detail elevation, partly in section, through the main pivot mechanism of the tool carrying frame.

Fig. 37 represents an enlarged detail section through the said pivot mechanism and associated parts.

Fig. 38 represents an enlarged detail section taken in the plane of the line XXXVIII—XXXVIII of Fig. 4, looking in the direction of the arrows.

Figs. 39 to 46 inclusive, represent diagrammatic views showing various positions of the cutting tool, its supporting frame, and the work during the operation of the machine.

Fig. 47 represents a detail side elevation, on the scale of Fig. 2, showing a modified form of work holding supports and tool carrying frame, and

Fig. 48 represents a detail top plan view of this form of tool carrying frame.

Referring to the preferred form shown in Figs. 1 to 46 inclusive, the machine comprises a base portion which takes the form of a hollow casing 1, (see Figs. 1 and 2). This casing may consist of a convenient metallic construction, such as cast iron, and its upper surface is provided with a pair of transversely extending grooves 2, 3, (see Figs. 2, 3 and 4), whereby the said upper surface of the base has three laterally extending and upwardly projecting rails or tracks 4, 5, 6, upon which a main traveling bed 7 is designed to rest and have a reciproca-

tory movement laterally across the base 1. The bed 7 has downwardly projecting guides 8, 9, which abut opposite sides of the track 6, and it is also provided with similarly depending front and back guides 10, 11, 70 which engage the tracks 4, 5, and carry gibbs 12, 13, for holding the bed 7 against vertical movement away from the base 1.

As above noted, the main traveling bed 7 is calculated to reciprocate across the machine during the operation thereof. I will now proceed to describe the means for imparting this motion.

An electric motor 14 (see Fig. 2), is secured to the main stanchion 15 which is bolted to and projects upwardly from the base 1, at the rear of the latter. The driven gear 16 of this motor is in mesh with a gear 17 fixed upon a shaft 18 (see Fig. 11) that is journaled in a gear casing 19 which is secured to the side of the stanchion 15 in front of the motor 14.

The shaft 18 has a pair of gears 20, 21, fixed against rotation but slidably mounted thereon, which gears are designed to alternately mesh with gears 22, 23, respectively, fixed on a shaft 24 that is mounted in the casing 19 below the shaft 18. This shaft 24 also carries a set of four gears 25, which are fixed thereto. The gears 25 vary in size and are adapted for driving engagement with a gear 26, which is slidably mounted but fixed against rotation upon the shaft 27 journaled in the casing 19 near the bottom thereof, through the intermediation of a floating gear 27* that is carried by the brackets 28 which are mounted to rock on the shaft 27. The brackets 28 may be provided with a suitable handle projecting exteriorly of the casing for the manual operation of the same, and thus it will be clear that the gear 26 may be slid along the shaft 27 and the floating gear 27*, carried by the brackets 28, caused to bring the said gear 26 into operative engagement with any one of the four gears 25, for changing the speed of rotation of the shaft 27.

The shaft 27 projects forwardly from the casing 19, into the interior of the base 1 where its front end is journaled in a bracket 29 fixed upon a housing 30 located within the said base. This front end of the shaft 27 carries a worm 31 that meshes with a worm wheel 32 which is fixed upon the end of a shaft 33 rotatably mounted at the lower part of the housing 30 (see Fig. 12). For the purpose of lubrication, the lower part of the worm wheel 32 enters an oil reservoir 34 that is bolted to the housing 30.

The shaft 33 carries a gear 35 which meshes with a gear 36 on a shaft 37; and it also carries a gear 38 which engages an idler gear 39, which latter in turn meshes with a gear 40 upon the shaft 37. Thus, the driven gear 35 is adapted to impart motion 1.0

in one direction to the gear 36, while the driven gear 38 is adapted to impart motion in a reverse direction to the gear 40. The gears 36 and 40 are rotatably mounted on the 5 shaft 37, but they are adapted to be fixed against rotation thereon by the clutch members 41, 42, which are splined to the shaft 37 and adapted to be brought into and out of engagement with the clutch faces on the 10 gears 36 and 40 respectively, in a well understood manner.

The shaft 37 extends laterally and projects through the left-hand side of the base 1 (see Fig. 5), in which it is journaled, as 15 clearly shown at 43 in Fig. 12. Fixed to the end of the said shaft is a gear 44 which meshes with a gear 45 fast on a stub shaft 46 which projects from the side of the base 1. This gear 45 in turn engages a gear 47 (see Fig. 4) 20 that is loosely mounted upon the end of a power screw 48 which extends laterally from side to side of the base 1 and has its ends fitted in bearings secured thereon. This screw 48 is in threaded engagement with the 25 lower part of the main traveling bed 7, as clearly shown in Fig. 9, so that rotation of the screw 48 in one direction will feed the bed 7 laterally across the base 1, while the reverse rotation of the said screw will 30 reverse the traveling direction of the bed 7.

In order to impart this rotation to the screw 48, a clutch sleeve 49 is keyed to the said screw, which sleeve has a clutch face adapted for co-operative engagement with 35 a clutch face on the gear 47 (see Fig. 22). A hand rod 50 is mounted in the base 1 parallel to the screw 48, and has a link 51 engaging the sleeve 49. It will be seen that the operator, by grasping the knob 52 which 40 is secured to the end of the rod 50, may so actuate the rod and link 51 as to throw the clutch sleeve 49 into and out of engagement with the gear 47, thereby locking and releasing the said gear to and from the screw 45 48. Accordingly, since the shaft 37 is driven from the motor 14 through the train of gearing already described, and since the shaft 37 is also connected to the screw 48 through the gearing last described, it will be 50 observed that when the shaft 37 is rotated, the screw 48 will also be rotated (providing the clutch 49 is locked to the gear 47), and the direction of rotation of the screw 48 will be determined by the direction of rotation 55 of the shaft 37, which latter is controlled by the operation of the clutch 41, 42. And, since the screw 48 is in threaded engagement with the traveling bed 7, the rotation of the former serves to feed the said bed laterally 60 across the machine.

In order to cause this motion of the traveling bed 7 to be reciprocatory, I have provided means for automatically engaging the clutch 41, 42, alternately with the gears 36 65 and 40 on the shaft 37, the shifting of the

clutch occurring at the end of each movement or stroke of the traveling bed 7. This means for shifting the clutches 41, 42 is under the control of the said traveling bed and will now be described.

A short rocking shaft 52 (see Figs. 5, 12 and 14), is mounted in a bearing on the top of the housing 30, and projects through the front of the base 1. The rear end of this shaft has a yoke 53 splined thereto, which 70 yoke engages the clutch members 41, 42, for sliding them upon the shaft 37. The forwardly projecting end of the shaft 52 has a cross arm 54 loosely mounted thereupon. One end of this cross arm 54 projects upwardly into the path of stops 55 (see Figs. 7 and 8), which are slidably mounted upon the gib 12, that is secured at the front of the traveling bed 7, as already described. It will be seen that these stops 55 have a 80 dove-tailed engagement with the said gib and that thumb screws 56 are provided for securing the stops in various adjustments along the traveling bed 7. A pair of fingers 57 (referring again to Figs. 5 and 14), 85 project upwardly from their common hub which is keyed to the shaft 52, as clearly shown at 58 in Fig. 14. These two fingers curve forwardly into the plane of movement of the upper part of the cross arm 54, so as 90 to limit the motion of the latter in a rotary direction with respect to the shaft 52. Each of these fingers 57 also carries an adjustment screw 59 for the purpose of determining the freedom of movement allowed the 95 upper part of the cross arm 54, within or between the said fingers 57.

From the arrangement just described, it will be clear that when, during the traveling movement of the bed 7, one of the stops 55 105 contacts with the upper projection of the cross arm 54, it will swing the latter until it engages one of the screws 59 in a finger 57, whereupon the continued movement of the stop 55 will serve to impart movement in 110 a rotary direction to the shaft 52. This latter movement will swing the yoke 53, and thus engage the clutch 41, 42, with the gear 36 or the gear 40. For the same reasons, the engagement of the other stop 55 with the 115 arm 54, during the reverse movement of the traveling bed 7, will swing the clutch 41, 42, into engagement with the other of the gears 36, 40. Inasmuch as the stops 55 are carried by the traveling bed 7, it will be seen that 120 the latter automatically controls its reciprocatory movement by causing the direction of the drive which feeds it to be reversed at the end of each of its movements or strokes. The possibility of adjusting the stops 55 enables the movement of the traveling bed 7 125 to be predetermined as to length within the range of the machine's capacity or size.

In order to provide rapid movement of the cross arm 54 and the yoke 53 which is 130

operated thereby, so that the clutch 41, 42, may be quickly and positively engaged and disengaged with and from the gears 36 and 40, and prevented from coming to rest in a neutral position, I provide a spring-actuated auxiliary shifter 60 (see Figs. 5, 19, 20 and 21), which is pivoted at the front of the housing 30, as indicated at 61, and which is normally urged downwardly by the retraction spring 62. This shifter has a beveled nose which is adapted for coöperation with a similarly beveled lug 63 secured to the lower extension of the cross arm 54. By this arrangement, as the arm 54 is swung in one direction, the nose of the shifter 60 will rise up to the apex of the lug 63 (see Fig. 20), and the instant it passes the said apex, the spring 62 will impel it to travel rapidly down the opposite inclined surface of the lug, thereby quickly swinging the cross arm 54 so as to rapidly move the clutch from engagement with one of the gears 36, 40, positively into engagement with the other, thereby insuring the continued reciprocation of the bed 7. In the reverse movement of the cross arm 54, the action of the shifter 60 will be similar but in an opposite direction. For the purpose of effective lubrication, the lower end of the arm 54 and the lug 63 are immersed in oil contained in a pot 54* secured to the front of the base 1.

The machine includes a pair of sliding supports 64, 65, (see Figs. 2, 4, 6, 7 and 8), for carrying the work and pattern holders. These supports are calculated to reciprocate forwardly and backwardly on the machine and hence to move transversely to the movement of the traveling bed 7. To this end, the bed 7 has three grooves 66, 67, 68, (see Figs. 6 and 9), fashioned in the top thereof, which leaves four up-standing rails 69, 70, 71, 72, upon which the supports 64, 65, are adapted to slide. By reference to Fig. 9, it will be seen that the rails 69 and 72 project laterally for carrying gibs 73, 74, so as to hold the supports 64, 65, against vertical displacement. Each of the supports also has a tongue 75, 76, the one projecting from the support 64 and the other from the support 65. These tongues are grooved for engagement with the rails 70, 71, respectively, and the supports are hollowed out so as to permit the tongue 75 to pass under the support 65 and the tongue 76 to similarly pass under the support 64. The provision of the tongues enables the supports to have long and effective guide bearings, and the arrangement whereby each projecting tongue passes under the other support permits this advantage to be obtained without sensibly increasing the bulk of the machine.

Means is provided for feeding these supports step by step across the traveling bed 7, either in the same direction or in oppo-

site directions, and this means, which is driven from the mechanism that actuates the traveling bed 7, as already described, will now be detailed.

The shaft 37 (see Figs. 5, 6, 12 and 26), has its outwardly projecting end reduced for the reception of a friction clutch which comprises the disks 77, 78, that are splined to the said shaft and the intermediate plate 79 which is loosely mounted upon the hubs 75 of the disks 77, 78.

Friction rings, which may be composed of such material as leather, are denoted by 80, 81, and are interposed between the disks 77, 78 and the plate 79. An expansion spring 82 which surrounds the end of the shaft 37 and abuts the disk 78 and a nut 83, serves to normally press the said disks together so as to cause the plate 79 to be yieldingly moved in a rotary direction corresponding to the movement of the shaft 37.

The plate 79 has a link 84 pivoted thereto, the other end of which link is also pivoted, as shown at 85, to a cross arm 86 (see Figs. 4 and 5), that is fixedly mounted upon an oscillating shaft 87 which is journaled in brackets 88, 89, secured to the front of the base 1, near the opposite sides thereof. A curved finger 90 projects from the bracket 88 into the path of movement of the said cross arm. An adjusting screw 91 is threaded in the end of the finger 90 and is calculated to abut the adjacent end of the cross arm 86, so as to limit the movement of the latter and hence determine the degree of oscillation allowed the shaft 87. A lock nut 92 serves to fix the screw 91 in any selected adjustment.

From the construction just described, it will appear that when the shaft 37 starts to rotate in one direction, it will swing the cross arm 86, through the connecting linkage, and hence rock the shaft 87. This rocking movement imparted to the shaft 87 will be first in one direction for a short distance and then in the reverse direction for a short distance as the point at which the link 84 is pivoted to the clutch plate 79 first rises and then falls in the movement of the said plate, and the extent or arc of the rocking motion will be determined by the adjustment of the screw 91. The continued rotation of the shaft 37 in the same direction will have no further effect upon the shaft 87, as the friction clutch 77, 78, 79 will slip. However, as soon as the direction of rotation of the shaft 37 is reversed, the cross arm 86 will again be actuated so as to rock the shaft 87, as just described. This procedure will continue as long as the machine is in operation. Therefore, inasmuch as the direction of rotation of the shaft 37 is controlled by the movement of the traveling bed 7, which reverses the said shaft when it reaches the end of each stroke, the rock-

ing shaft 87 is rocked once forward and backward for each motion of the traveling bed 7. This movement of the linkage which actuates the shaft 87, is well illustrated in 5 Figs. 27, 28 and 29. The purpose of this construction and operation just described is to feed the work and pattern holder supports 64, 65, step by step across the machine transversely to the movement of the travel- 10 ing bed 7, so that the cutting tool may operate successively upon all portions of the die to be cut, as will be hereafter described; and I shall now proceed to set forth the mechanism by which the rocking movement 15 of the shaft 87 serves to impart motion to the said supports.

A segmental helical gear 93 (see Figs. 25, 20 30, 31 and 32), is slidably keyed to the shaft 87, and this gear meshes with another seg- 25 mental gear 94, which is integral with a sleeve 95 that is loosely mounted upon a bearing 96 which is secured to the bed 7 by cap screws 96*, (see Figs. 5 and 6). The bearing 96 has a pair of depending cheeks 25** which slidably engage the shaft 87 at either side of the gear 93, and thus serve as means to reciprocate the latter on the shaft 87, so as to maintain it in mesh with the gear 94 during the operation of the 30 machine.

A feed screw 97 is rotatably mounted in the bearing 96, and its protruding end carries an integrally formed ratchet and gear 98, 99, which is splined thereto. The ratchet 35 98 has its periphery provided with a double set of ratchet teeth which are oppositely inclined, for alternate engagement with a pawl 100 that is pivotally mounted at the top of the sleeve 95. This pawl, which is 40 clearly illustrated in Figs. 30, 31, 32, has a double set of points arranged side by side, one of which lies in the same plane as one set of teeth on the ratchet 98, while the other lies in the same plane as the other set 45 of teeth. Thus, the pawl may be swung into operative engagement with either set of teeth on the ratchet 98, in an obvious manner.

The construction just described enables 50 the oscillating shaft 87 to impart a slow step by step rotary motion to the screw 97, since the gear 93 rocks with the shaft 87 and in turn oscillates the sleeve 95 and pawl 100 carried thereby. Each complete cycle 55 of oscillation of the shaft 87, which includes one movement in each direction as already described, first pushes the ratchet 98 the distance predetermined by the adjustment of the screw 91 and then retracts the pawl so 60 that it engages a preceding tooth. It will be clear that the direction of rotation thus transmitted to the feed screw 97, will be determined by which ever set of teeth on the ratchet 98 the pawl 100 engages.

65 The feed screw 97 is threaded into the

work holder support 64 (see Figs. 6 and 7), so as to cause the latter to move slowly across the main traveling bed 7, as the said screw is rotated. Mechanism is also provided for similarly actuating the work 70 holder support 65, which mechanism consists of a shaft 101 (see Figs. 6 and 8), that is journaled in a bracket 102 which is formed integrally with the bearing 96; the inner end of which shaft is coupled to a feed screw 75 103 that is threaded into the work holder support 65, as clearly shown in Fig. 8. The protruding end of the shaft 101 has a gear 104 fixed thereto, which gear is arranged to mesh with the gear 99 that is integral with 80 the ratchet 98. Thus, the rotary movement engendered in the feed screw 97, also serves to impart a rotary movement, in the opposite direction, to the shaft 101, and hence to the feed screw 103 which controls the 85 movement of the work holder support 65.

As the feed screws 97 and 103 are threaded in the same direction, their movement, just described, will cause the work and pattern holder supports 64, 65, to move across the 90 main traveling bed 7 in opposite directions. In case it is desired to have the said supports move in the same direction, the coupling which connects the shaft 101 with the feed screw 103 may be disconnected (see 95 Figs. 23, 24), by removing one of the pins 105; and the two supports 64, 65, may be locked together by bolts 106 which are fitted to pass through lugs 107 (see Figs. 9 and 10), at each side of the said supports. Spac- 100 ing sleeves 108 may be interposed between the lugs 107 surrounding the bolts 106, for determining the distance between the supports 64, 65. In this condition both of the 105 said supports travel under the influence of the feed screw 97 which is in direct engagement with the support 64.

Referring now to the general operation, it will be observed that the shaft 37 imparts a reciprocating movement (through the de- 110 scribed connections) to the main traveling bed 7, which latter automatically reverses the direction of rotation of the shaft 37, and hence the direction of its own movement, at the end of each traverse of the machine, and 115 that the length of its reciprocating strokes may be adjusted at will. While this is going on, the same shaft 37, through other linkage, imparts a very slow intermittent movement to the work and pattern holder supports 64, 65, transverse to the path of movement of the bed 7, and this movement of the supports may be such that they are moving in 120 the same direction or in opposite directions. Hence a tool mounted, at the time of starting 125 the machine, in a fixed position at one corner of a die or pattern carried by the supports, would be caused to successively engage the entire surface of the work or pattern as a result of the combined movements just 130

described, because the motion imparted to the work and pattern holder supports feeds them very slowly in a given direction under said tool, while the motion of the traveling bed 7 relatively rapidly reciprocates them in a transverse direction.

If the work and pattern holder supports are so connected as to move in the same direction, a right-hand die will be cut from a right-hand pattern; while, if the said supports are actuated in opposite directions, a left-hand die will be cut from a right-hand pattern, or vice versa; and the said dies may, in either case, be of any size within the capacity of the machine.

Before departing from the description of these parts of the machine, it may be noted that the feed screws 48, 97 and 101—103, are all provided with squared ends which are fitted to receive a hand crank (see Fig. 3), for manually operating them. In this manual operation of the screw 48, the clutch 49 will be disengaged (see Fig. 9). In the case of the screws 97 and 101, 103, assuming that it is desired to move the supports 64, 65, independently of each other, the gear 104 may be removed from the shaft 101 by releasing the set screw 109 (see Fig. 6).

The work and pattern holders, one of which is adapted to carry the die to be cut and the other the pattern, are carried by the supports 64, 65. They are identical in construction and mounting, and each is composed of two parts 110, 111, and 112, 113 respectively (see Figs. 7 and 8). The parts 110, 112 are provided with depending circular pivots 114, 115, as shown in dotted lines, which enter correspondingly shaped recesses formed in the tops of the supports 64, 65, whereby the said parts 110, 112 may be arcuately adjusted in a horizontal plane upon the supports. Curved slots 116, 117, (see Fig. 6), are fashioned in the ends of the said parts 110, 112, and cap screws 118, 119, are fitted therein and threaded into the supports 64, 65, for securing the parts 110, 112 in the desired arcuate adjustment.

The upper parts 111, 113 of the work holders are semicylindrical in form and are fitted to rest in the concave upper surfaces of the parts 110, 112, as clearly shown in Figs. 7 and 8. They are hollowed out and provided with transverse slots 120, 121, as shown in dotted lines, which are traversed by locking screws 122, 123, threaded into the parts 110, 112. This arrangement enables the upper parts 111, 113, of the work holders to be arcuately adjusted in a vertical plane and locked in any desired adjustment.

The double adjustment just described for the work and pattern holders permits the work and pattern to be held in any desired angular position for the purpose of making angular cuts, and this may be accomplished

without any change in the adjustment or operation of the cutting tool.

The work, or die to be cut, is denoted by 124, and may be temporarily secured to the part 111 of the work holder by bolts fitting in T-shaped slots 125 and serving to draw down on straps 125* which rest on the face of the die and on struts 125**. The pattern 126, from which the die is to be cut, is similarly secured to the part 113 of the pattern holder, the slots in this case being denoted by 127.

From the foregoing it will be clear that the said holders, and hence the die and pattern, are arranged to partake of all the motions imparted to the supports 64, 65, hereinabove described.

Turning now to the tools and means for operating them, I will first describe the roughing tool and its operating mechanism, attention being directed to Figs. 1 and 2.

A cross-head 128 is fixed to the top of the main stanchion 15, and this cross-head has its front end bifurcated to form bearings 129, 130 for a spindle 131 which carries the roughing tool 132. A pair of pulleys 133, 134, are splined to, but in sliding engagement with, the spindle 131, and are located between the bifurcations of the cross-head 128.

The driven gear 16 of the motor 14 engages a gear 135 which is fixed to a shaft 136 housed in the casing 137 secured to the side of the stanchion 15 above the casing 19. This shaft 136 carries a train of change speed gears which are adapted to mesh with a gear fixed upon the shaft 138, one end of which is journaled in the casing 137, while the other end finds a bearing in a bracket 139 that is bolted to the rear of the stanchion 15. This shaft 138 has a pair of pulleys 140, 141, fixed thereto. Idler pulleys 142 are mounted in a rearward extension of the cross-head 128, as clearly shown in Fig. 2. Thus, the arrangement is such that a belt, (not shown), may be caused to engage either of the pulleys 133, 134, then pass over the idlers 142 and engage either of the pulleys 140, 141. In this condition, when rotation is imparted to the shaft 138 from the motor 14, the spindle 131, which carries the roughing tool 132, will be caused to rotate.

A vertically adjustable carriage 143 is mounted at the front of the stanchion 15, just below the cross-head 128, and this carriage may be moved to various vertical adjustments by the operation of a screw 144 to which is fixed a hand wheel 145. The carriage 143 also has, in slidable connection therewith, a bearing 146 in which the lower end of the spindle 131 is fixed against longitudinal movement. Means is provided for vertically adjusting the spindle 131 and bearing 146 with respect to the carriage 143,

which means consists of a screw 147 that is mounted in a bracket 148 on the carriage 143, and has its lower end threaded into a lug 149 on the bearing 146. A bevel pinion 5 150 is fixed to the top of the screw 147 and meshes with a similar bevel pinion 151 which is designed to be operated by a hand wheel 152. Thus, the rotation of the hand wheel will vertically adjust the spindle, as mentioned.

The roughing tool may be a routing tool or a hubbing tool or a cherrying tool or any other form of cutter, as the nature of the work may require, and it will be seen that 15 this mechanism is adapted for feeding it into engagement with the work which is carried and moved as already described.

As indicated at the outset, one of the important features of my invention resides 20 in the construction and arrangement of the tool carrying frame and associated parts whereby the sinking operation is rendered not only accurate and expeditious, but additionally, the cutting of vertical walls in 25 the dies may be automatically accomplished. I will now proceed to describe this part of the machine, and direct attention particularly to Figs. 1, 2, 3, 33, 34, 35, 36 and 37.

The vertically movable carriage 143 has 30 downwardly extending arms 153 projecting from the left-hand side thereof, in the lower end of which arms are formed bearings 154 fitted to receive the ends of a rocking pivot 155 which is mounted in a horizontal 35 plane and extends longitudinally of the machine, that is, from the front toward the back. A stop 156 projects downwardly from the pivot 155 and is adapted to contact with the adjusting screw 157 threaded in a 40 cross-bar 158 that is bolted to the bearings 154. Thus, the screw 157 is arranged to limit the rocking movement of the pivot 155 in one direction.

The said pivot has a pair of short arms 45 159 formed integral with and extending downwardly from its ends, exterior to the bearings 154. The lower parts of these arms 159 have depressions 160 fashioned therein for receiving the pointed ends of screws 50 161 which serve to fulcrum or pivot the tool carrying frame 162. Thus, the said frame may be swung or oscillated for a certain distance about the pivot 155, and it may also be rocked about its own fulcrum point 55 constituted by the screws 161.

The frame 162 is substantially pentagonal in shape, as clearly shown in Figs. 3 and 33, and its two inner apices are provided with vertical bearings 163, 164, for rotatably 60 mounting the spindles 165, 166, which respectively carry the cutting tool 167 and tracer 168. It will be understood, of course, that the said spindles are adapted to carry any form of tool which is designed for a 65 purpose within the field of operation of the

machine, and that the positions of the tracer and cutter may be reversed or two tools of the same kind may be mounted in the spindles, if desired.

The screws 161 which fulcrum the frame 70 162, are located toward the rear or outer end thereof, and, in order to balance the frame so that the tools may be very delicate in their operation in traversing the pattern and work, I provide a weight 169 which is adjustably secured on a tail 170 that projects outwardly or rearwardly from the frame.

A pair of arms 171 project downwardly from the vertically movable carriage 143 at the side thereof opposite the arms 153, and 80 they support, at their extremities, a bearing 172 in which is mounted a short rocking shaft 173 which has a depending lug 174. A coupling 175 is pivoted to the lug 174 and has a threaded engagement with a 85 rod 176, the other end of which is threaded into a coupling 177 that is pivoted in a yoke 178 formed upon the inner side of the tool frame 162. The rod 176 may be adjusted in the couplings 175 and 177 so as to raise 90 or lower that side of the frame 162 in which the tools are mounted. A cross-bar 179 is carried at the front lower portion of the bearing 172, and it supports an adjusting screw 180, one end of which is fitted to contact with and limit the movement of the lug 174 in one direction in a manner similar to that in which the rocking movement of the pivot 155 is limited by the screw 157, as already described.

It should be here noted that the lug 174 is located at a point considerably higher than the yoke 178, so that the rod 176 projects upwardly from the frame 162 to the lug 174 at an angle of substantially fifteen 100 or twenty degrees to the horizontal. Thus, any pull which may, in effect, be exerted by the rod 176 upon the frame 162 will be, to a certain extent, a lifting pull. Similarly, it should be noted that the fulcrum screws 110 161 which pivot the frame 162, are located above the operating points of the tools 167, 168, so that an imaginary line extending from the said screws to the tool points would be at an angle of substantially fifteen degrees to the horizontal. Hence, any pull which is, in effect, exerted at the fulcrum screws 161 of the frame 162, to move the tool to the left with respect to the work, will be, to a certain extent, a lifting pull.

Means is provided for alternately locking the stop 156 and lug 174 against the adjusting screws 157 and 180 respectively, so that the stop 156 will be locked while the main traveling bed 7 of the machine is 125 moved to the right or away from said stop and the lug 174 will be locked when the said bed is moving to the left or away from it.

This means comprises a longitudinally reciprocating shaft 181 which has an inter- 130

- mediate screw threaded portion 182 that is in engagement with a threaded bushing 183 rotatably journaled in a bearing 184 formed in the lower inner part of the arms 153.
- 5 One end of this shaft 181 enters the bearing 172 and projects in proximity to the lug 174, while the other end is slidably mounted in a depending bracket 185 formed at the lower part of the arms 153. The part of the shaft 181 which is between the bearing 184 and bracket 185, has fixed thereto a guide 186 in which is threaded an adjustable abutting rod 187, one end of which projects in proximity to the stop 156, while the other passes 10 through a lug at the bottom of the bearing 184 and has a milled handle 188 for manual adjustment.
- From the above description, it will be seen that if the bushing 183 is rotated, its 20 screw threads will feed the shaft 181 in one direction so as to cause the rod 187 to abut the stop 156 and move the latter until it impinges against the adjusting screw 157, while the reverse rotation of the bushing 183 25 will cause the upper extremity of the shaft 181 to engage the lug 174 and force it against the adjusting screw 180. Thus, the stop 156 and lug 174 may be alternately locked as above indicated, so as to change the 30 point of effective pull exerted upon the tools to suit the movement of the traveling bed 7, and hence of the pattern and work, so that there will be a resistance or effective pull exerted upon the tools during the operation 35 of the machine at an angle of approximately fifteen degrees above the horizontal, which will result in a tendency to lift the tools in case any obstruction to their horizontal movement is encountered.
- 40 The mechanism for alternately reciprocating the shaft 181 in opposite directions consists of a sprocket chain 189 which passes around a sprocket wheel 190 that is fast to the face of the bushing 183. This chain 45 passes upwardly around the sprockets 191, 192, 193, (see dotted lines, Fig. 2), and thence downwardly to a sprocket 194 that is carried upon a stub shaft 195 mounted in a boss 196 secured to the main stanchion 15 50 at the side thereof opposite the gear castings 19 and 137, (see Figs. 6 and 38). The sprocket 194 is fitted to be frictionally engaged with the shaft 195 by means of the clutch members 197, 198, which are keyed to the said shaft and provided with leather faces 199, 200, in engagement with the sprocket 194. The clutch member 198 has a sprocket 201 screwed thereto, and a coiled spring 202, which abuts the said sprocket 55 and adjusting nuts 203, serves to normally hold the clutch members 197, 198, in frictional clutching engagement with the sprocket 194. A second sprocket chain 204 surrounds the sprocket 201 and passes forwardly through the base 1 of the machine, 60

into engagement with a sprocket 205 which is keyed upon the shaft 37 (see Fig. 5).

Thus, the shaft 181 is reciprocated in unison with the rotation of the shaft 37, and, as will be remembered, the rotation of the latter is automatically reversed at the end of each traverse or stroke of the main traveling bed 7.

I also provide means for rotating the tools 75 167, 168, which means consists of an electric motor 206, (see Fig. 33), that is carried on the frame 162. The driven shaft of the motor carries a grooved pulley 207 around which a belt 208 is fitted to pass. The belt then engages guide pulleys 209, and finally 80 encompasses a double-grooved pulley 210 which is fixed to the top of the spindle 166. By this arrangement, the cutter 167 may be positively rotated during the operation of the machine, and, if desired, a second belt or 85 cord may be passed around the pulley 210 and around the pulley 211 which is similarly fastened to the top of the spindle 166, that normally carries the tracer 168 for rotating the latter. 90

As is well understood to operatives in this art, it is very desirable, in certain classes of work, to have the tools positively rotated, while this is not necessary in other classes of work. Thus, the means which I have 95 just described may be utilized or not at the discretion of the operator.

The arrangement of the tool holding frame which enables the latter to cut vertical walls or walls as nearly vertical as may 100 be desired in the final product, is, as I have already stated, of major importance and one of the most valuable features of my invention. Consequently, I have endeavored to clearly set forth this operation in the dia- 105 grammatic views represented in Figs. 39 to 46 inclusive, of the drawings, in which figures I have used the same reference numerals as have already been applied in the description of the several parts. 110

The die to be cut or work 124 is indicated in Fig. 39 as moving to the right with the travel of the bed 7 (not shown). The cutting tool 167 has just encountered a vertical wall which it is desired the tool shall 115 cut and climb. In this condition, the shaft 181 has been moved, as already described, so as to lock the stop 156 between the pin 157 and the end of the rod 187, which, in effect, forms part of the shaft 181. Thus, 120 the parts are locked so that the tool carrying frame 162 may be swung on its pivot screws 161. It will be seen, therefore, that, as the work continues its movement to the right as denoted by the arrow, there is a 125 pull exerted on the tool and tracer in the direction of the line marked 212, which, as the drawing indicates, is about fifteen degrees above the horizontal line 213. Under these circumstances, the contact between the 130

tracer and the upright wall of the pattern will cause the tracer and, hence, the tool to swing upwardly around the pivot 161 and climb the vertical wall, during which movement the pivot point or fulcrum at the coupling 175 and the other pivot point at the shaft 173 are free to permit the movement of the adjacent parts. After the tool has climbed the vertical wall, the work is at the limit of its movement, at which time the direction of movement of the work or die is reversed and, immediately, the shaft 181 is caused to travel in the opposite direction so as to lock the lug 174 between the adjusting screw 180 and the end of the shaft 181, as clearly shown in Fig. 41. In this condition, the tool travels along the depression in the die until it meets another vertical wall, as shown in Fig. 42. As the work continues its movement in the direction which is indicated by the arrow, there is, in effect, a pull exerted upon the yoke 178, which pull is in the direction of the line 214, which is about twenty degrees above the horizontal indicated by the line 215. Under these conditions, the tool will climb the vertical wall as indicated in Fig. 43. It will then descend into the second depression, as indicated in Fig. 44, and finally climb the last, as indicated in Figs. 45 and 46. In Fig. 46 the cycle of movements is again about to start.

It will be seen from the foregoing that I have provided an arrangement in which there is what I choose to call, for want of a better phrase, a "double fulcrum" construction, whereby the tool holding frame is caused to operate about a pivot at one side of the work while the latter is moved in one direction, and about another pivot at the opposite side when the work is moving in the reverse direction. Thus, whenever the tool encounters a vertical obstruction in the contour of the die, it is at once influenced by an effective pull in a line above the horizontal so as to enable it to swing upwardly and transverse the said obstruction. So far as I know, in the machines heretofore used in this art the tools could not climb an obstruction which was less than ten degrees from the vertical, and, consequently, a great deal of hand work was necessary after the operation of the machine had terminated, if the die was to be provided with vertical walls.

I believe that the operation of the machine will be apparent to anyone skilled in this industry, from the foregoing description of the construction and individual operation of the several elements or groups of elements; but I may briefly summarize the same, as follows:

The main traveling bed 7 is driven back and forth across the machine by the actuating and reversing mechanism. At the same time the work holders are fed transversely, very slowly, across the traveling

bed, either in the same direction or in directions opposite to each other; the latter movement being for the purpose of cutting a left-hand die from a right-hand pattern or vice versa. During this operation, the working tool and tracer are held, by a very nicely pivoted and balanced arrangement, in engagement with the work and pattern and, after the work holders have made one complete travel across the main reciprocating bed, the tools have contacted with or traversed every portion of the face of the work and pattern. This operation is all automatic. After one die has been completed, another piece of work may be suitably placed in position, the pawl 100 reversed so as to engage the other set of teeth on the ratchet 98, and the machine again set in operation, during which all the parts will operate as before except that the work holders will move in the direction or directions opposite to their former travel. It is, of course, understood that upon the initiation of the work, the roughing tool 132, carried by the spindle 131, may be used for roughly cutting out, "hogging" out, "hubbing" out, or other preliminary work, as is the practice in the art.

Whenever it is desired to make an angular cut or to facilitate the tools in their operation of cutting steep or difficult walls, the work may be adjusted angularly in either a horizontal or vertical plane, or both, by moving the parts 110, 111, and 112, 113 of the work and pattern holders. Both holders will, under such an exigency, be adjusted to the same angular position.

Referring to the modified form shown in Figs. 47 and 48, the parts are the same as those described in the preferred form except that plates 216, 217, are secured by screws 218, 219, to the upper parts 111, 113, respectively, of the work holder supports. The plate 216 is double, that is, it is adapted to support a die 220 and a pattern 221; while the plate 217 is adapted for supporting a single die 222. The dies and pattern may be secured to the plates by T-bolts and straps as is the case with the preferred form.

Both end spindles 165 and 166 of the tool carrying frame 162 are provided with cutting tools for engaging the dies, and a third bearing 223 is fashioned on the frame 162, intermediate the spindles 165, 166, for the reception of a spindle 224 that is calculated to carry a tracer 225 for engagement with the pattern 221. The spindle 224 has a pulley 226 from which a driving cord or belt 227 may be passed to the pulley 211 on the spindle 166, for suitably driving the tracer 225, when desired.

It will be noted that the arrangement is such that the tracer is located nearer to the spindle 165 than to the spindle 166, and that, to be exact, it is spaced from the spin-

dle 165 one-third of the distance between the spindles 165 and 166.

By the arrangement just described, a right, and its mating left hand die, may be 5 simultaneously cut from a single pattern. The operation of the machine is the same in the use of this modified form of work holders and tool carrying frame as is the case when the preferred form is being employed.

10 I believe that the arrangement of the tool carrying frame, which I have referred to as the "double fulcrum" construction, is wholly novel both in its operation and effect, in this class of machinery broadly; that is, whether 15 reference be had to die sinking machines strictly or to beveling machines or milling machines, etc. Consequently, when in the claims I refer to an "engraving machine," I use the expression broadly and intend to 20 cover all machines of this general class, and do not intend to limit myself to die sinking machines proper. Again, I am aware that many of the features of my invention may be applied to machines in which the work 25 and pattern holders and their supports operate in a vertical plane or in a plane at some other angle to the horizontal, and I do not intend to limit my claims of invention to machinery in which those parts operate in 30 a horizontal plane.

Consequently, it will be understood that various changes may be resorted to in the form, construction and arrangement of the several parts without departing from the 35 spirit and scope of my invention, and hence I do not wish to be limited to the details herein shown and described except as they may be specifically included in the claims.

What I claim is:

40 1. In a machine of the character described, a traveling bed, work and pattern holders carried thereby, said holders being angularly adjustable in their plane of travel about vertical axes so as to simultaneously move 45 opposite parts of each holder in different directions, means for moving the holders forward and backward on the bed, and means for mounting tools in engagement with the work and pattern.

50 2. In a machine of the character described, work and pattern holders, means for moving said holders, said holders being provided with substantially centrally located pivots whereby they may be rotatably adjusted in their plane of travel, and means for mounting tools in engagement with the work and pattern.

60 3. In a machine of the character described, a traveling bed, work and pattern holders carried thereby, means for independently arcuately adjusting the holders in a plane substantially at right angles to their plane of travel, means for moving the holders on the bed, and means for mounting tools in engagement with the work and pattern.

4. In a machine of the character described, a traveling bed, work and pattern holders carried thereby, means for independently arcuately adjusting the holders in a plane substantially at right angles to their plane 70 of travel, means for moving the holders forward and backward on the bed, and means for mounting tools in engagement with the work and pattern.

5. In a machine of the character described, 75 work and pattern holders, said holders being provided with substantially centrally located pivots whereby they may be rotatably adjusted in one plane, means for arcuately adjusting said holders in another 80 plane substantially at right angles to the first named plane, and means for mounting tools in engagement with the work and pattern.

6. In a machine of the character described, 85 work and pattern holders, and roughing, finishing and tracing tools mounted for engagement with the work and pattern.

7. In a machine of the character described, 90 work and pattern holders, and reciprocatable roughing, finishing and tracing tools mounted for engagement with the work and pattern.

8. In a machine of the character described, 95 work and pattern holders, a support, and roughing, finishing and tracing tools mounted in said support for engagement with the work and pattern, said support being adjustable with respect to the said holders.

9. In a machine of the character described, 100 work and pattern holders, a support, and roughing, finishing and tracing tools mounted in said support for engagement with the work and pattern, said support being adjustable with respect to the said holders, 105 and said roughing tool being adjustably mounted on the said support for independent movement with respect to the holders.

10. In a machine of the character described, 110 a traveling bed, work and pattern holders carried thereby, means for moving the holders on the bed, and roughing, finishing and tracing tools mounted for engagement with the work and pattern.

11. In a machine of the character described, 115 a traveling bed, work and pattern holders carried thereby, means for moving the holders on the bed at an angle to the path of movement of the bed, and roughing, finishing and tracing tools mounted for engagement with the work and pattern.

12. In a machine of the character described, 120 a traveling bed, work and pattern holders carried thereby, means for moving the holders forward and backward on the bed, and roughing, finishing and tracing tools mounted for engagement with the work and pattern.

13. In a machine of the character described, 125 work and pattern holders, means

- for independently universally adjusting the holders, and means for mounting tools in engagement with the work and pattern.
14. In a machine of the character described, work and pattern holders, means for independently universally adjusting the holders, means for imparting traveling movement to the holders, and means for mounting tools in engagement with the work and pattern.
15. In a machine of the character described, work and pattern holders, means for independently universally adjusting the holders, means for imparting traveling movement to the holders in opposite directions, and means for mounting tools in engagement with the work and pattern.
16. In a machine of the character described, work and pattern holders, means for independently universally adjusting the holders, means for imparting simultaneous traveling movement to the holders in opposite directions either toward or away from each other, and means for mounting tools in engagement with the work and pattern.
17. In a machine of the character described, work and pattern holders, means for independently universally adjusting the holders, automatic means for imparting traveling movement to the holders, and means for mounting tools in engagement with the work and pattern.
18. In a machine of the character described, work and pattern holders, means for independently universally adjusting the holders, automatic means for imparting traveling movement to the holders in opposite directions, and means for mounting tools in engagement with the work and pattern.
19. In a machine of the character described, work and pattern holders, means for independently universally adjusting the holders, automatic means for imparting simultaneous traveling movement to the holders in opposite directions either toward or away from each other, and means for mounting tools in engagement with the work and pattern.
20. In an engraving machine, means for carrying the work, a tool mounted for engagement with the work, means for causing relative reciprocating lateral movement of the tool and work, and means for exerting a pull on the tool at an acute angle to the plane of movement of the work when it encounters an obstruction in the work during relative movement in either direction.
21. In an engraving machine, means for carrying the work, a tool mounted for engagement with the work, automatic means for causing relative reciprocating lateral movement of the work and tool, and means for exerting a pull on the tool at an acute angle to the plane of movement of the work
- when it encounters an obstruction in the work, during relative movement in either direction.
22. In an engraving machine, means for carrying the work and pattern, tools mounted for engagement with the work and pattern, means for causing the relative reciprocating lateral movement of the tools and work and pattern, and means for exerting a pull on the tools at an acute angle to the plane of movement of the work and pattern when they encounter obstructions in the work and pattern during relative movement in either direction.
23. In an engraving machine, means for carrying the work and pattern, tools mounted for engagement with the work and pattern, automatic means for causing relative reciprocating lateral movement of the tools and work and pattern, and means for exerting a pull on the tools at an acute angle to the plane of movement of the work and pattern when they encounter obstructions in the work and pattern during relative movement in either direction.
24. In an engraving machine, means for carrying the work, a frame for mounting a tool for engagement with the work, means for causing relative lateral movement of the tool and work, and means for pivoting the frame at either side of the work.
25. In an engraving machine, means for carrying the work, a frame for mounting a tool for engagement with the work, means for causing relative lateral movement of the tool and work, and means for pivoting the frame at either side of the work to swing in a vertical plane.
26. In an engraving machine, means for carrying the work, a frame for mounting a tool for engagement with the work, means for causing relative lateral movement of the tool and work, and means for automatically pivoting the frame at either side of the work.
27. In an engraving machine, means for carrying the work, a frame for mounting a tool for engagement with the work, means for causing relative lateral movement of the tool and work, and means for automatically pivoting the frame at either side of the work to swing in a vertical plane.
28. In an engraving machine, means for carrying the work, a frame for mounting a tool for engagement with the work, means for causing relative lateral reciprocating movement of the work with respect to the tool, and means for pivoting the frame at the side of the work opposite to the direction in which the work is moving.
29. In an engraving machine, means for carrying the work, a frame for mounting a tool for engagement with the work, and means for causing relative lateral reciprocating movement of the work with respect

to the tool, and means for pivoting the frame at the side of the work opposite to the direction in which the work is moving to swing in a vertical plane.

5 30. In an engraving machine, means for carrying the work, a frame for mounting a tool for engagement with the work, means for causing relative lateral reciprocating movement of the work with respect to the tool, and means for automatically pivoting the frame at the side of the work opposite to the direction in which the work is moving.

10 31. In an engraving machine, means for carrying the work, a frame for mounting a tool for engagement with the work, means for causing relative lateral reciprocating movement of the work with respect to the tool, and means for automatically pivoting the frame at the side of the work opposite to the direction in which the work is moving.

15 32. In an engraving machine, means for carrying the work, a frame for mounting a tool for engagement with the work, means for reciprocating the work laterally with respect to the tool, and means for alternately pivoting the frame at the side of the work opposite to the direction in which the work is moving.

20 33. In an engraving machine, means for carrying the work, a frame for mounting a tool for engagement with the work, means for reciprocating the work laterally with respect to the tool, and means for alternately pivoting the frame at the side of the work opposite to the direction in which the work is moving to swing in a vertical plane.

25 34. In an engraving machine, means for carrying the work, a frame for mounting a tool for engagement with the work, means for reciprocating the work laterally with respect to the tool, and automatic means for alternately pivoting the frame at the side of the work opposite to the direction in which the work is moving.

30 35. In an engraving machine, means for carrying the work, a frame for mounting a tool for engagement with the work, means for reciprocating the work laterally with respect to the tool, and automatic means for alternately pivoting the frame at the side of the work opposite to the direction in which the work is moving to swing in a vertical plane.

35 36. In an engraving machine, means for carrying the work, a frame for mounting a tool for engagement with the work, means for causing relative lateral movement of the tool and work, said frame having a bodily movable pivot at each side of the work, and means for locking one of said pivots against bodily movement while permitting the frame to fulcrum thereon.

40 37. In an engraving machine, means for carrying the work, a frame for mounting a

tool for engagement with the work, means for causing relative lateral movement of the tool and work, said frame having a bodily movable pivot at each side of the work, and means for locking either of said pivots against bodily movement while permitting the frame to fulcrum thereon. 70

38. In an engraving machine, means for carrying the work, a frame for mounting a tool for engagement with the work, means for causing relative lateral movement of the tool and work, said frame having a bodily movable pivot at each side of the work, and means for alternately locking each of said pivots against bodily movement while permitting the frame to fulcrum thereon. 80

39. In an engraving machine, means for carrying the work, a frame for mounting a tool for engagement with the work, means for causing relative lateral movement of the tool and work, said frame having a bodily movable pivot at each side of the work, and means for automatically locking one of said pivots against bodily movement while permitting the frame to fulcrum thereon. 85

40. In an engraving machine, means for carrying the work, a frame for mounting a tool for engagement with the work, means for causing relative lateral movement of the tool and work, said frame having a bodily movable pivot at each side of the work, and means for automatically locking either of said pivots against bodily movement while permitting the frame to fulcrum thereon. 90

41. In an engraving machine, means for carrying the work, a frame for mounting a tool for engagement with the work, means for causing relative lateral movement of the tool and work, said frame having a bodily movable pivot at each side of the work, and means for automatically alternately locking each of said pivots against bodily movement while permitting the frame to fulcrum thereon. 100

42. In an engraving machine, a traveling bed for carrying the work, a frame for mounting a tool for engagement with the work, said frame having a bodily movable pivot at each side of the work, and means for locking one of said pivots against bodily movement while permitting the frame to fulcrum thereon, said last named means being controlled by the movement of the bed. 115

43. In an engraving machine, a traveling bed for carrying the work, a frame for mounting a tool for engagement with the work, said frame having a bodily movable pivot at each side of the work, and means for locking either of said pivots against bodily movement while permitting the frame to fulcrum thereon, said last named means being controlled by the movement of the bed. 120

44. In an engraving machine, a traveling bed for carrying the work, a frame for

- mounting a tool for engagement with the work, said frame having a bodily movable pivot at each side of the work, and means for alternately locking each of said pivots 5 against movement while permitting the frame to fulcrum thereon, said last named means being controlled by the movement of the bed.
45. In an engraving machine, means for carrying the work, a frame for mounting a tool for engagement with the work, means for causing relative lateral movement of the tool and work, said frame having two pivots at each side of the work, one pivot being 10 bodily movable and one fixed against bodily movement, and means for locking one of said bodily movable pivots against bodily movement while permitting the frame to fulcrum thereon.
- 15 46. In an engraving machine, means for carrying the work, a frame for mounting a tool for engagement with the work, means for causing relative lateral movement of the tool and work, said frame having two pivots at each side of the work, one pivot being 15 bodily movable and one fixed against bodily movement, and means for locking one of said bodily movable pivots against bodily movement while permitting the frame to fulcrum thereon.
- 20 47. In an engraving machine, means for carrying the work, a frame for mounting a tool for engagement with the work, means for causing relative lateral movement of the tool and work, said frame having two pivots at each side of the work, one pivot being 20 bodily movable and one fixed against bodily movement, and means for locking either of said bodily movable pivots against bodily movement while permitting the frame to fulcrum thereon.
- 25 48. In an engraving machine, means for carrying the work, a frame for mounting a tool for engagement with the work, means for causing relative lateral movement of the tool and work, said frame having two pivots at each side of the work, one pivot being 25 bodily movable and one fixed against bodily movement, and means for alternately locking each of said bodily movable pivots against bodily movement while permitting the frame to fulcrum thereon.
- 30 49. In an engraving machine, means for carrying the work, a frame for mounting a tool for engagement with the work, means for causing relative lateral movement of the tool and work, said frame having two pivots at each side of the work, one pivot being 30 bodily movable and one fixed against bodily movement, and means for alternately locking each of said bodily movable pivots against bodily movement while permitting the frame to fulcrum thereon.
- 35 50. In an engraving machine, means for carrying the work, a frame for mounting a tool for engagement with the work, means for causing relative lateral movement of the tool and work, said frame having two pivots at each side of the work, one pivot being 35 bodily movable and one fixed against bodily movement, and means for alternately locking each of said bodily movable pivots against bodily movement while permitting the frame to fulcrum thereon.
- 40 51. In an engraving machine, means for carrying the work, a frame for mounting a tool for engagement with the work, means for causing relative lateral movement of the tool and work, said frame having two pivots at each side of the work, one pivot being 40 bodily movable and one fixed against bodily movement, and means for alternately locking each of said bodily movable pivots against bodily movement while permitting the frame to fulcrum thereon.
- 45 52. In an engraving machine, a traveling bed for carrying the work, a frame for mounting a tool for engagement with the work, said frame having two pivots at each side of the work, one of said pivots being 45 bodily movable and the other fixed against bodily movement, and means for locking one of said bodily movable pivots against bodily movement while permitting the frame to fulcrum thereon, said means being controlled by the movement of the bed.
- 50 53. In an engraving machine, a traveling bed for carrying the work, a frame for mounting a tool for engagement with the work, said frame having two pivots at each side of the work, one of said pivots being 50 bodily movable and the other fixed against bodily movement, and means for locking either of said bodily movable pivots against bodily movement while permitting the frame to fulcrum thereon, said means being controlled by the movement of the bed.
- 55 54. In an engraving machine, a traveling bed, work and pattern holders carried thereby, means for moving the holders in the same direction on the bed, spacing members for maintaining the holders a predetermined distance apart, means for locking the holders together in abutting engagement with the spacing members, and means for mounting tools in engagement with the work and pattern.
- 60 55. In an engraving machine, work and pattern holders, a support for the said holders, means for moving the holders on the support, one of said holders having a lateral projection which provides an elongated guide bearing for the said holder on the support, and means for mounting tools in engagement with the work and pattern.
- 65 56. In an engraving machine, work and pattern holders, a support for the said holders, means for moving the holders on the support, said holders having lateral projections which provide elongated guide bear-

ings for the said holders on the support, and means for mounting tools in engagement with the work and pattern.

57. In an engraving machine, a traveling bed, work and pattern holders carried thereby, means for moving the holders on the bed, one of said holders having a laterally projecting tongue which provides an elongated guide bearing for the said holder on the bed, 10 and means for mounting tools in engagement with the work and pattern.

58. In an engraving machine, a traveling bed, work and pattern holders carried thereby, means for moving the holders on the bed, 15 said holders having laterally projecting tongues which provide elongated guide bearings for the said holders on the bed, and means for mounting tools in engagement with the work and pattern.

20 59. In an engraving machine, work and pattern holders, a support for said holders, means for moving the holders on the support, said holders having lateral projections which provide elongated guide bearings for 25 the holders on the support, and being cut away so as to permit the said projections to slide thereby, and means for mounting tools in engagement with the work and pattern.

60. In an engraving machine, a traveling bed, work and pattern holders carried thereby, means for moving the holders on the bed, one of said holders having a laterally projecting tongue which provides an elongated guide bearing for the said holder on the bed, 35 the other holder being cut away so as to permit the said tongue to slide thereby, and means for mounting tools in engagement with the work and pattern.

61. In an engraving machine, a traveling bed, work and pattern holders carried thereby, means for moving the holders on the bed, said holders having laterally projecting tongues which provide elongated guide bearings for the said holders on the bed, said 45 holders being cut away so as to permit the said tongues to slide thereby, and means for mounting tools in engagement with the work and pattern.

62. In an engraving machine, a plurality 50 of work holders and a pattern holder, means for moving a work holder and a pattern holder in one direction, means for moving another work holder in the opposite direction, and means for mounting cutting tools 55 in engagement with the work and a tracing tool in engagement with the pattern, whereby a plurality of dies may be simultaneously cut from a single pattern.

63. In an engraving machine, a reciprocating bed, a plurality of work holders and a pattern holder carried thereby, means for moving a work holder and a pattern holder in one direction on the bed, means for moving another work holder in the opposite direction on the bed, and means for mounting 65

cutting tools in engagement with the work and a tracing tool in engagement with the pattern, whereby a plurality of dies may be simultaneously cut from a single pattern.

64. In an engraving machine, a traveling bed, a combined work and pattern holder carried thereby, another work holder also carried thereby, means for moving the holders on the bed, and means for mounting a cutting tool and a tracer in engagement with the work and pattern on the combined holder and a cutting tool in engagement with the work on the other holder.

65. In an engraving machine, a traveling bed, a combined work and pattern holder carried thereby, another work holder also carried thereby, means for moving the combined holder and the other holder in opposite directions on the bed, and means for mounting a cutting tool and a tracer in engagement with the work and pattern on the combined holder and a cutting tool in engagement with the work on the other holder.

66. In an engraving machine, die supporting means comprising a slidable support and a die holder, said holder including two members, one of said members being mounted on the support for adjustment in a rotary direction about a central point in substantially the same plane as the sliding movement of the support, and the other member being mounted on the first named member for arcuate adjustment in a plane substantially at right angles to the plane of adjustment of the first named member.

67. In an engraving machine, pattern supporting means comprising a slidable support and a pattern holder, said holder including two members, one of said members being mounted on the support for adjustment in a rotary direction about a central point in substantially the same plane as the sliding movement of the support, and the other member being mounted on the first named member for arcuate adjustment in a plane substantially at right angles to the plane of adjustment of the first named member.

68. In an engraving machine, die and pattern supporting means comprising slidable supports and die and pattern holders, each of said holders including two members, one of said members being mounted on a support for adjustment in a rotary direction about a central point in substantially the same plane as the sliding movement of the support, and the other member being mounted on the first named member for arcuate adjustment in a plane substantially at right angles to the plane of adjustment of the first named member.

69. In an engraving machine, die and pattern supporting means comprising, slidable supports and die and pattern holders, each of said holders including two members,

of said members being mounted on a support for adjustment in a rotary direction about a central point in substantially the same plane as the sliding movement of the 5 support, and the other member being mounted on the first named member for arcuate adjustment in a plane substantially at right

angles to the plane of adjustment of the first named member, and means for locking the 10 said members in various adjustments.

In testimony that I claim the foregoing as my invention I have signed my name this 21st July, 1917.

WALTER E. SARGENT.
